UNITED STATES PATENT OFFICE.

CHARLES A. FISHER, OF CHICAGO, ILLINOIS.

MATTRESS.

SPECIFICATION forming part of Letters Patent No. 771,867, dated October 11, 1904.

Application filed December 29, 1902. Serial No. 136,951. (No model.)

To all whom it may concern:

Be it known that I, CHARLES A. FISHER, a citizen of the United States, residing at Chicago, in the county of Cook and State of Illinois, have invented certain new and useful Improvements in Mattresses, of which the following is a specification.

My invention relates more especially to mattresses of cotton-batting and like material, although adapted to mattresses filled with other resilient fibrous material.

The object of my invention is to simplify and cheapen the manufacture of such mattresses and to produce a more symmetrical and smooth-surfaced mattress.

These and other objects as may hereinafter appear are accomplished by the construction shown in the accompanying drawings, in which—

Figure 1 is a side elevation of a block of cotton-batting or like material suitable to fill a mattress. Fig. 2 is a perspective view of the block overlaid with a sheet of fabric such as is shown in Fig. 3. Fig. 3 is a representation of the fabric. Fig. 4 is a perspective view of the block having a sheet of fabric arranged upon the upper and lower surfaces thereof and having a sheet of cotton-batting or like material arranged over each of the sheets of fabric. Fig. 5 is an end view of Fig. 4. Fig. 6 is a perspective view of a block partly sewed. Figs. 7 and 8 show details of the sewing, and Fig. 9 is a perspective view of a completed mattress having one corner thereof broken away.

Like letters of reference indicate the same parts in the several figures of the drawings.

Taking for illustration the use of cotton-batting, with which are made the so-called "elastic-felt" mattresses, a block or body of cotton-batting sufficient to properly fill a mattress will when not confined, as shown in Fig. 2, be of much greater thickness than the finished mattress. If now such a sheet of batting is confined within a tick in the ordinary manner, the tick and filling being quilted together the result will be a mattress having a quilted surface and hollow edges.

With my improved mattress I first prepare the block of filling as a separate entity com-

plete in itself, and after the block has been prepared by being confined in the manner shown by me to the desired thickness, while at the same time retaining a symmetrical contour, it is inserted in the tick, to which it is secured by a line of stitching adjacent to its edges, thereby producing a symmetrical mattress with smooth surfaces and slightly-rounded edges which is at the same time resilient and yet is so constructed as to resist all strains tending to displace the filling laterally.

Having arranged a block A of cotton-batting of the desired shape and size, I place on the top and bottom surfaces thereof a sheet of fabric B, preferably of a loose texture, such as burlap, which will serve effectively to confine the batting, will readily admit of the passage of needles, and will at the same time give the filling-block a very considerable tensile strength. Over each of these layers of fabric I spread a thin layer of cotton-batting C, which serves to hold the loops of the thread D and keep them from pulling through the fabric. By means of threads D, which are sewed through the upper and lower thin layers of batting, the intermediate layers of fabric, and the main body of filling, I compress the block to the required thickness, or I compress it in any suitable manner and secure it at the proper thickness by means of such threads, which can be run through without any regard to symmetry, as they are concealed when the mattress is filled, and so require no especial care or skill in the forming of the filling-block. When this is done, as shown at the right end of Fig. 6, I have produced a symmetrical, resilient, and durable block with substantially smooth upper and lower surfaces which needs only to be slid into a smoothly-fitting tick E, and while it need not necessarily be secured to the tick a more satisfactory and pleasing effect is attained by securing it to the tick, preferably by running a seam diagonally through the top of the tick, the corner or edge of the filling, and out again at the sides of the tick, as shown in Fig. 9.

I claim—

1. A block of filling for mattresses and the like, comprising a block of resilient material

having substantially the length and breadth of the completed mattress, a sheet of fabric of the same length and breadth, covering the upper and lower faces of said block of material, a comparatively thin sheet of resilient tufting material, of the same length and breadth, covering said sheets of fabric, and stitches confining all of said layers to the required thickness.

10 2. A mattress comprising a block of resilient material, a sheet of fabric, of substantially the same length and breadth as said block, covering the upper and lower faces of

said block, a comparatively thin sheet of resilient material covering said sheets of fabric, 15 said block and said sheets of fabric and sheets of resilient material being sewed together and confined to the required thickness by stitches, said block, so prepared, being then inserted in a tick and secured thereto by marginal 20 stitching extending through said tick and through said prepared block.

CHARLES A. FISHER.
